ABSTRACT OF THE DISCLOSURE

In the die casting of molten metal, for example ferrous or high-temperature metals having temperatures in the range of 2600° F. to 3500° F., the molten metal is introduced into an injection cylinder and the metal is normally moved by a reciprocating plunger from the injection cylinder into the die cavity. The extreme heat from the metal within the injection cylinder chamber can damage the plunger. This is overcome by having a plurality of plungers so arranged so that the plungers are sequentially positioned to be used in the injection cylinder chamber, thus minimizing distortion and permitting each plunger to cool before it is again utilized to move molten metal.

SUMMARY OF THE INVENTION

This invention relates to a die casting method and apparatus in which a plurality of sequentially positioned plungers are used to move molten metal from a die casting injection cylinder.

Another purpose is a die casting apparatus for use with high temperature molten metals utilizing a plurality of sequential plungers for preventing plunger distortion due to contact with the molten metal.

Other purposes will appear in the ensuing specification, drawings and claims.

BRIEF DESCRIPTION OF THE DRAWINGS

The invention is illustrated diagrammatically in the following drawings wherein:

FIG. 1 is an axial section through a die casting apparatus of the type described, and

FIG. 2 is an end view of the plunger cylinder illustrated in FIG. 1.

DESCRIPTION OF THE PREFERRED EMBODIMENT

In the die casting of high temperature molten metals, for example in the range of 2600° F. to 3500° F., it has been found that the end of the plunger which contacts the molten metal to move it into the die cavity becomes distorted. Such distortion can damage the plunger to the point where it will not move within the injection cylinder. To overcome the problem of temperature distortion, we utilize a plurality of sequentially operated plungers, there being a sufficient time lapse between the use of each plunger such that it can cool down to a satisfactory temperature. It is the continuous uninterrupted use of the same plunger at high temperatures which causes distortion.

In FIG. 1, an injection cylinder is indicated generally at 10 and there may be an interior chamber 12 defined by a sleeve 14. The injection cylinder may take a variety of different forms, however, as shown herein, the cylinder is made up of laminations which are specifically designed to prevent temperature distortion within the injection cylinder itself. Surrounding the lamination 14 there is an intermediate layer or lamination 16 and

2

there may be an outer lamination or outer shell 18. The outer layer 18 is formed of a high strength steel, for example a steel having the designation H13 has been found to be satisfactory. A beryllium copper alloy having high heat conductivity has been found to be satisfactory for the intermediate layer 16. A heat resistant material, for example Rene 41, one of the group of metals known as "Super Alloys," has been found to be satisfactory for the inner layer 14. It is important that the outer layer have high strength; the intermediate layer have high heat conductivity; and the inner layer have a high degree of heat resistance.

Because temperature distortion is not only a problem with the face of the plunger, but it is also a problem in the injection cylinder itself, it is desired in some applications to heat the injection cylinder to a temperature approximating that of the temperature inside of the chamber 12 when there is metal in it. For example, a plurality of axially extending electric rods 20 may be positioned within the intermediate layer 16. These rods are effective to bring the interior of the injection cylinder or the chamber 12 up to a temperature such that the introduction of molten metal into the chamber will not cause non-linear temperature distortion.

25 The invention should not be limited to an injection cylinder which is heated by any particular means. For example, heating coils may be wound around the injection cylinder, or there may be an injection cylinder which is heated by hot gases. What is important is to prevent temperature distortion of the injection cylinder.

In like manner, the invention should not be limited to an injection cylinder which is heated. In some applications, cooling fins which extend radially out from the injection cylinder may be utilized to rapidly dissipate the 35 additional heat added to the injection cylinder by the introduction of molten metal therein. In such instances, temperature distortion is minimized and, to a large extent, eliminated by the rapid dissipation of heat from the injection cylinder.

40 It is important to have some means in the injection cylinder for eliminating non-linear temperature distortion. Otherwise, although the plunger may have means for compensating for high temperatures, it can still cause damage to the injection cylinder if the temperature of the injection cylinder is not itself also stabilized.

The injection cylinder 10 may have an open end 22 which has direct access to a die cavity. The cover side of the die is indicated at 24 and may be suitably attached to a platen 26 by means of a platen adapter or the like 50 28. The details of the die and the attachment of the die to the injection cylinder are not important. What is important is to provide a die casting injection cylinder which can readily introduce molten metal directly into the die cavity. The injection cylinder may be completed 55 by a molten metal feed passage 30 which opens into the chamber 12 at the end of the chamber away from the open end 22.

A cylinder is indicated generally at 32 and may include a plurality of axially extending passages 34. Within each of the passages 34 is a plunger 36. Each of the plungers is of a size and is so arranged that when it is in axial alignment with the chamber 12, it may be operated to drive molten metal within the chamber 12 into the die cavity. The mechanism for actually operating the plungers may be conventional and may be of the general type used with the single plunger arrangements now in use in injection cylinders. At the center of the cylinder 22 is a shaft 38 about which the cylinder rotates. The mechanism for rotating the cylinder 32 may be conventional. One requirement is that the timing of the rotation of the injection cylinder 32 be coordinated with

the introduction of molten metal through the passage 30 into the chamber 12.

At the far right-hand side of FIG. 1 the plungers are all mounted in a support member 40. In normal operation, each of the plungers will be individually operated by suitable hydraulic, pneumatic, or other satisfactory operating means. As illustrated particularly in FIG. 2, there are a plurality of plungers 36 arranged in a circular or cylindrical alignment. As the cylinder 32 rotated about its shaft 38, or about its axis, the plungers 36 will sequentially be positioned for use in the injection cylinder. By having a plurality of plungers, it is possible for each of the plungers to cool down before the sequential operation will require the use of that particular plunger again.

The invention should not be limited to any particular arrangement for moving the sequentially positioned plungers. What is important is to provide a plurality of plungers, which can be used in sequence, and means for moving the plungers so that their sequential operation is assured. The particular makeup of the plunger is not important, nor is its size or shape. The invention is particularly directed to eliminating temperature distortion at the end 42 of the plunger which is actually in contact with the molten metal when the plunger is within the injection cylinder.

As mentioned above, the means for eliminating temperature distortion of the injection cylinder itself may vary. The injection cylinder may be heated to provide a crucible effect. In other applications, the injection cylinder may be rapidly cooled by the use of radiating fins, again to eliminate temperature distortion.

Whereas the preferred form of the invention has been shown and described herein, it should be realized that there are many modifications, substitutions and alterations thereto within the scope of the following claims.

What is claimed is:

1. In a system for die casting molten metal, a mold having an input opening, an injection cylinder positioned adjacent said mold, an open-ended chamber in said injec-

tion cylinder, a molten metal feed passage opening into said chamber, one open end of said chamber being in alignment with said mold input opening, a plurality of injection cylinder plungers, carrier means supporting said plungers and adapted for positioning one of said plungers at the other open end of said chamber for use in injecting molten metal from the chamber into the mold, and means supporting said carrier means and adapted for moving said plurality of plungers, as a group, for positioning different plungers at the other open end of said chamber.

2. The structure of claim 1 further characterized in that said carrier means is a rotatable cylinder.

3. The structure of claim 2 further characterized in that said supporting means has an axis offset from the axis of said injection cylinder chamber.

4. The structure of claim 1 further characterized in that said molten metal feed passage is adjacent the other open end of said chamber.

5. The structure of claim 1 further characterized in that said supporting means adapted for moving said plungers is effective to sequentially position said plungers at the other open end of the chamber.

6. The structure of claim 1 further characterized by and including means for reducing temperature distortion of the injection cylinder.
